US00D936633S

(12) **United States Design Patent** (10) Patent No.: **US D936,633 S**
Lee et al. (45) Date of Patent: **** Nov. 23, 2021**

(54) **COMBINED PAIR OF WIRELESS
EARPHONES AND CRADLE**

(71) Applicant: **LG ELECTRONICS INC.**, Seoul (KR)

(72) Inventors: **Gayeong Lee**, Seoul (KR); **Gangho Woo**, Seoul (KR); **Soonhyun Park**, Seoul (KR); **Byunghyun Yi**, Seoul (KR)

(73) Assignee: **LG ELECTRONICS INC.**, Seoul (KR)

(**) Term: **15 Years**

(21) Appl. No.: **35/509,566**

(22) Filed: **Dec. 12, 2019**

(80) **Hague Agreement Data**

Int. Filing Date: **Dec. 12, 2019**
Int. Reg. No.: **DM/208221**
Int. Reg. Date: **Dec. 12, 2019**
Int. Reg. Pub. Date: **Jun. 12, 2020**

(30) **Foreign Application Priority Data**

Aug. 26, 2019 (KR) 30-2019-0040772

(51) **LOC (13) Cl.** **14-01**

(52) **U.S. Cl.**

USPC **D14/205**; D13/108; D3/218
